(57) **CLAIM**

The ornamental design for a collar for animals, as shown and described.

DESCRIPTION

FIG. 1 is a front, right and top perspective view of a collar for animals, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an enlarged view of an area labeled 8 in FIG. 1. In FIGS. 3, 6, and 7, the evenly-spaced broken lines depict portions of the collar for animals that form no part of the claimed design.

1 Claim, 8 Drawing Sheets
